OTTO HAAKH, OF ROTTERDAM, NETHERLANDS

DEVICE TO BE APPLIED TO CIGARS

Application filed February 27, 1930, Serial No. 431,865, and in the Netherlands January 13, 1930.

The invention relates to a device to be applied to a cigar with ornamental and/or tax bandrol, by which the idea has been realized to combine the means for lighting the cigar, entirely or partly, so as to form one entirety. It is therefore no longer necessary to carry these lighting means or at any rate part of them and one is therefore always assured of the possibility to light the cigar one wishes to smoke.

According to the invention therefore a match has been arranged to the ornamental and/or tax bandrol fixed around the cigar. If this is a "strike anywhere" match, one has all that is necessary for lighting the cigar. In the event that it is a match, which requires a special striking surface, my invention enables to arrange to one of the sides of the ornamental and/or tax bandrol a striking surface for such matches.

In the accompanying drawing by way of example only a perspective image of a cigar, provided with the device according to the invention, is shown.

10 Around the cigar 1 an ornamental bandrol 2 is arranged which at the side of the cigar is provided with a strip 3 with striking mass for lighting a match 4; this match, preferably of flat shape, being kept between the bandrol 2 and the strip 3.

I claim:—

15 A match securing device adapted to be applied to a cigar comprising a bandrol having a free end, a strip extending longitudinal-
20 ly of said bandrol under said free end, means upon said strip for striking the match and said free end having means thereon for securing a match between said free end and said means upon said strip so that said match
25 is not easily dislodged.

30 In testimony whereof I affix my signature.
OTTO HAAKH.
